UNITED STATES PATENT OFFICE

CLARENCE WINFRED SPICER, OF PLAINFIELD, NEW JERSEY

FENCE MATERIAL AND METHOD OF MAKING THE SAME

Application filed July 17, 1928. Serial No. 293,439.

My invention relates to fencing material more particularly to wire fence fabrics of various mesh which are sold in rolls to be erected on posts or poles and has for its object the production of a roll of fencing that is convenient and easily handled and erected without any great effort on the part of those constructing the fence.

When wire fence material is fabricated out of wire as heavy as No. 12 wire or heavier it is quite a heavy task to unwind the roll prior to stringing it on the posts or poles. An object of my invention is to overcome this objectionable feature.

15 My roll has rolled within the roll a pull wire that can be utilized to unroll the fence fabric easily and quickly.

The foregoing and other features of my invention will now be described in connection with the accompanying drawings forming part of this specification in which similar characters of reference indicate like parts after which I shall point out in the claims those features which I believe to be new and 25 desire to secure by Letters Patent.

In the drawings:

Figure 1 illustrates method of preparing wire fence fabric and method of unwinding.

Figure 2 shows the fence fabric before it 30 is rolled up.

Figure 3 shows a modified form of my fencing similar to that shown in Figure 2.

Figure 4 is a diagrammatic sketch showing a transparent roll of fence fabric with the 35 separate pull wire coiled within the roll.

In the carrying out of my invention I may use any wire fence fabric 10 which is usually sold in rolls.

Before the roll of wire fabric is rolled up 40 into a roll I fasten a separate pull wire 11 to the edge of the fabric 12 and then roll up the strip of fence fabric 10 with the separate wire 11 longitudinally disposed throughout the length of fence fabric until it is in 45 the form shown in Figure 4. In Figure 3, I show two such separate wires 11. It will be readily understood that any number of wires 11 may be used. On the end of the wire 11 opposite the end fastened to the wire fence 50 fabric I provide a hitch 13 of any convenient

style adapted to be held and pulled by horse or tractor or any means convenient at the time of erecting the fence on the posts 16.

It will be observed by referring to Figure 1 that after the loose end of the fence fabric 55 is secured to a post by pulling the pull wire 11 the roll of fabric will be unrolled at the same time tension is given to the fencing.

I do not wish to limit myself to unrolling the roll in a vertical position as the roll may 60 be laid on the ground and by pulling the pull wire 11 the roll can be unrolled and straightened before putting on the posts.

I wish it distinctly understood that my roll of fence fabric and the method of making 65 same herein illustrated and described is in the form in which I desire to construct it and that any changes or modification may be made as may be convenient or desirable without departing from the salient features of my 70 invention and I therefore intend the following claims to cover such modifications as naturally fall within the lines of invention.

I claim:

1. A roll of fence material with a separate 75 pull wire rolled longitudinally of the fence material whereby the fence material will be unrolled when the pull wire is pulled.

2. A roll of fence material with a plurality of pull wires rolled longitudinally of the 80 fence material whereby the fence material will be unrolled when the pull wire is pulled.

3. A roll of fence material with a separate pull wire rolled therein, the inner end of the pull wire fastened to the inner edge of the 85 roll and the other end provided with a gripping means whereby the fence material will be unrolled when the pull wire is pulled.

Dated this 16 day of July, 1928.

CLARENCE WINFRED SPICER. 90
